UNITED STATES PATENT OFFICE.

JAMES H. DUNCAN AND SYDNEY BOGOW, OF NEW YORK, N. Y.

CONCRETE JOIST FLOOR FORMS.

Application filed February 9, 1923. Serial No. 617,905.

This invention pertains to the art of molding in situ floor slabs with joists integral with such slabs, and the objects in view are, first, to so relate the molding devices to the 5 under framing or shoring that the construction of the latter is simplified by the omission of parts without loss of function; second, to provide for an adjustment of the forms in a manner to mold joists or beams 10 the depth of which is variable; and, third, to provide for the removal of the forms when the slab shall have become set without disturbing the supports for the joists or beams, thus making the forms available for use in 15 other false work while the shoring or under framing and the soffit boards remain in place for a desired period of time in order to support the joists or beams until the concrete becomes set and hardened.

20 To these ends, our invention embodies soffit planks set in edgewise relation to the shoring or under framing, soffit members usually in the form of boards resting upon the upper edges of the soffit planks, forms each 25 provided with flanged lower edges and positioned for contact with the edges of the soffit members so as to occupy a cooperative relation thereto and produce the mold cavity for the beams or joists, and means for supporting 30 the forms in fixed positions and at desirable heights relatively to the soffit members, whereby each form may be collapsed relatively to the molded material and withdrawn from contact therewith.

35 In one embodiment of the invention, the displaceable forms are imposed upon stretchers which span the spaces between the soffit planks so as to act as stays for the latter, and to the soffit planks are attached 40 cleats or battens upon which the stretchers are supported and along which the stretchers are supported and along which the stretchers may be adjusted or shifted to positions required for the proper upholding of the 45 forms, whereby the stretchers may be positioned in proper relation to the displaceable forms and said stretchers may be displaced from the cleats or battens in order to make way for the withdrawal of the forms.

50 A preferred embodiment of the invention utilizes a plurality of form-supporting members composed of metal and attachable individually to the soffit planks adjacent the lap between the meeting ends of the metal 55 forms. Each form-supporting member is

constructed to perform the double function of confining the form sidewise against the soffit member and of supporting in part the weight of the displaceable unitary form, said member being attachable easily to the soffit plank as by a nail, or its equivalent, and said member is shiftable or removable from an operative position with reference to the form or forms so as to provide for the withdrawal of the same without disturbing the position of the soffit planks and boards relatively to the concrete.

50 It is preferred, also, to stiffen each displaceable form internally thereof with a view to precluding the inward collapse of the form under the pressure of the molded material, and to this end an internal brace may be wedged into frictional contact with the sides of the form or said brace may be pivotally mounted on the stretcher in a position for wedging contact with the form.

60 Other functions and advantages of the invention will appear from the following description taken in connection with the drawings, wherein—

65 Figure 1 is a side elevation partly in section of our form for molding a floor slab with integral joists.

70 Figures 2 and 3 are vertical cross sectional views illustrating different positions of the displaceable form for molding joists of different depths.

75 Figures 4, 5 and 6 of the drawings illustrate a preferred embodiment of the invention, wherein are used a plurality of metal form-supporting members in operative relation to the soffit planks and the displaceable unitary forms; Figure 4 being a longitudinal sectional elevation; Figure 5 a vertical transverse section, and Figure 6 a detail perspective view of one of the metal supporting members.

80 A are the soffit planks set in edgewise relation to the under framing or shoring B, the latter comprising battens b and posts b' upon which the soffit planks are supported directly so as to afford a simple and economical structure composed of relatively few parts adapted to be installed quickly for service.

85 C are the soffit members which constitute the bottoms of the mold cavities for the joists of the monolithic floor structure. Said soffit members are shown as boards of a desired width and length, and they rest flat-

wise upon the upper edges of the planks A, being attached thereto by nails or otherwise if required.

D are the forms, each being shown as composed of metal and in a single piece, said form being adapted to be assembled as a unit and being removable in like manner. Each form is of a desired cross section, with its walls slightly diverging, and said form is provided at the lower free edges thereof with outwardly directed flanges d. Said form is of suitable length, and in assembling the pairs of forms they are positioned for the end edges thereof to be brought into contact, said forms having overlapping relation or endwise abutting contact. The forms D are positioned for the sides thereof to have contact with the edges of the soffit members C, but the flanges d of said forms extend below the soffit members and toward the soffit planks, said forms D being in co-operative relation to the soffit members C for producing therewith a mold cavity within which concrete material is poured for producing the floor joists integral with the floor slab.

For supporting the pan shaped forms in displaceable relation to the soffit members A, C, and the shoring, we may use form-supporting members of the character shown in Figures 1 to 3, inclusive, wherein battens E and stretchers F are positioned on the soffit planks for upholding the unitary forms, or we may use metal form-supporting members as shown in Figures 4 to 6, inclusive.

In the form shown in Figures 1, 2 and 3, the battens are fastened to the vertical sides of the planks A so as to extend lengthwise thereof and to remain in fixed positions thereon, whereas the stretchers F rest upon the battens so as to be free to move lengthwise of the battens. These stretchers are supported by the battens in movable relation to the soffit planks, and thus the stretchers are shiftable at will in order to occupy positions below the pan like forms at the meeting or lapping end portions of said forms, whereby forms of different lengths are adapted to be properly supported by the stretchers. The flanged lower edges of the forms rest directly upon the stretchers so that the weight of the forms is imposed upon the stretchers. Said stretchers are in contact at their end portions with the planks A and they perform the function of stays for the planks in order to preclude lateral bowing or displacement thereof.

Obviously, the battens E are attached to the planks A at a height suitable to support the forms at the required elevation with respect to the soffit members C. In Figure 2, the battens or cleats are fastened to the planks A at about midway the height thereof so as to support the forms in a raised position for molding a joist of a desired depth,

but in Figure 3 the battens or cleats E are fastened lower down on the planks A in order that the forms may be dropped down with reference to the soffit members C for molding a joist of decreased depth.

Means are provided interiorly of the form for precluding inward displacement of the walls thereof under the pressure of the material undergoing the molding operation. As shown in Figure 2, a strut G is wedged into contact with the opposite walls, and held immovably in position by frictional contact with the form, but in lieu of said strut we may use a bar G', see Figure 2, attached to one or more of the stretchers F and positioned for contact with opposite walls of the form at the lower edges thereof. Obviously, we may employ the strut G or the bar G', either or both of the same.

In lieu of using a straight bar, it may be desirable to employ props H adapted for contact separately with the opposite walls of said form, see Figure 3. Said props are pivotally connected at h to the stretcher F, and they are adapted to be forced into wedging engagement with the walls of the form for precluding the inward bending or collapse of the metal pan or form.

To use the apparatus, the under framing or shoring is erected with battens b, and the planks A are set up edgewise thereon. The cleats E are fastened at the proper height to the planks, soffit members C are placed upon the top edges of the planks, and stretchers F are positioned upon the cleats, after which the forms D are assembled into edgewise contact or into overlapping relation. The stretchers are shifted to fit beneath the lapping portions of the forms, and said forms rest upon the stretchers and into contact with the soffit members. After the concrete is poured, all the parts remain in place for a required time to permit the slabs to set, whereupon the stretchers are shifted out of place and the forms D are displaced from contact with the concrete, the flanged lower edges d of the forms moving downward away from the soffit members C and between the planks A. The forms are thus withdrawn without disturbing the planks and the soffit members, the same remaining in place for the time required in order that the mass of concrete constituting the joists may set and harden.

It is preferred to use form-supporting members I of the character disclosed in Figures 4, 5 and 6 of the drawings, said members performing the double function of clamping the unitary forms in sidewise relation to the soffit boards and of sustaining the weight of said unitary forms while permitting the ready withdrawal of said forms without disturbing the positions of the soffit boards and soffit planks. As in the construction of Figures 1, 2 and 3, the unitary forms

D are composed of metal in the form of inverted pans, and provided with flanges d at their lower edges, said forms being assembled in substantially aligned relation and with the end portions of each form overlapping similar end portions of an adjacent form, such overlap being indicated at d', Figure 4. The forms are positioned for the flanges d to extend below the soffit boards, free from contact therewith, so that the forms can be raised or lowered as required, but the respective side walls of the pans are in sidewise abutting relation to the edge portions of the soffit boards, see Figure 5.

15 Each member I is composed of metal, either in cast, wrought or struck up condition, said member being provided with a head i, an upstanding lug i' and a longitudinal slot i". The head i exceeds the thickness 20 of the shank constituting the body of said member, see Figure 6, and the lug i' extends upwardly from the head, at one end. The slot i" is shown as extending through the lower end of the body or shank. To use the 25 part I, it is positioned below the flanged edges d of the pans and at the overlap d' between two adjacent pans. The slotted body of the member is applied laterally against a face of the soffit plank A and occupies such relation thereto that the head i is in contact with the flanged lower edges d of the pan or pans, and the lug i' is in lateral contact with the pans at the lower open portion thereof. The member I is fastened in 35 place by driving a nail, spike, or other member j (one or more) through the slotted body and into the material of the soffit plank. Said member is thus adapted to be fixedly attached to the soffit plank at a point for 40 supporting the pan or pans at the required height with respect to the soffit boards, and in addition to sustaining the weight of the pans the members I are positioned for the lugs i" to bind against the pans on the inside thereof for the purpose of confining or 45 clamping the pan walls into sidewise contact with the soffit boards, see Figure 5, thereby imparting stability to the pans.

The pans D and members I are adapted 50 for ready and expeditious assemblage, but when it is desired to dismount the pans the members are detached from the soffit planks by drawing out the nail's, after which the unitary pans can be lowered and withdrawn 55 from the concrete without disturbing the soffit boards or soffit planks, thus enabling the pans to be re-used during the period required for the concrete to become set and hard.

60 Having thus fully disclosed the invention, what we claim as new and desire to secure by Letters Patent is:

1. In a concrete form, the combination

with a soffit member, and a form contacting therewith, of a plurality of form-retaining members each contacting with said form, said form-retaining member being mounted for slideable and pivotal movement relatively to said form.

2. In a concrete form, the combination 70 with a soffit member, a soffit plank, and a form positioned in contact with said soffit member, of a plurality of form-retaining members each having contact with an edge and the face of said form, said form-retaining member being mounted on the soffit plank for slideable and pivotal motion relatively to said form.

3. In a concrete form, the combination 80 with a soffit plank, a soffit member imposed thereon, and a form positioned for contact with an edge of said soffit member with the lower portions of the form extending below said soffit member, of a one-piece supporting and retaining member embodying a slotted 85 body and a flanged head, said slotted body being attached to the soffit plank at a point below the form and the flanged head being in contact with the lower part of the form.

4. In a concrete form, the combination 90 with a soffit plank, a soffit member imposed thereon, and a form positioned for contact with an edge of said soffit member with the lower portions of the form extending below said soffit member, of a one-piece supporting 95 and retaining member embodying a headed and slotted body attached to the soffit plank with the head in contact with the form, said supporting and retaining member being displaceable by a sliding and swinging movement relatively to the form.

5. In a concrete form, the combination 100 with a soffit plank, a soffit member and a form in contact with an edge of the soffit member, of a supporting and retaining 105 member embodying a slotted and headed body attached to the soffit plank below the form, said body member being positioned for the head to engage with the lower portion of the form.

6. In a concrete form, a form-supporting and retaining member embodying a slotted body and a head unitary one with the other, the slot in the body extending lengthwise thereof and the head being in offstanding 115 position with respect to the body.

7. In a concrete form, a form supporting member composed of a single piece of metal and embodying a slotted body, a head exceeding the thickness of the body, and a lug extending outwardly from said head.

In testimony whereof we have hereto signed our names this 7 day of Feb., 1923.

SYDNEY ROGOW.
JAMES H. DUNCAN.
